UNITED STATES PATENT OFFICE

JOHN A. MCKAY, OF COSHOCTON, OHIO, ASSIGNOR TO THE JONES METAL PRODUCTS COMPANY, OF WEST LAFAYETTE, OHIO, A CORPORATION OF OHIO

REFLECTOR HOLDER

Application filed March 28, 1931. Serial No. 525,963.

This invention relates to reflector holders and more particularly to a device for firmly attaching a lamp shade or reflector to a lighting fixture. My device is well adapted for use under very severe conditions, such as in connection with outdoor advertising signs, and in buildings containing heavy machinery and where there is constant vibration, which would be apt to loosen some prior types of reflector holders.

A general object of my invention is to provide a simple and economical device for firmly holding a reflector to a fixture. Another object is to provide a weatherproof reflector holder. Another object is to provide a device in which the reflector may be easily detached from the fixture or attached thereto. A further object is to provide a reflector holder, in which the reflector is held in position by a simple type of bayonet lock, and in which a further lock is provided to prevent the bayonet lock from jarring loose. Another object is to provide a reflector holder in which the reflector may be firmly held in a number of different positions.

Briefly, a reflector holder, made according to my invention, comprises a cup-shaped casting which is secured to the ordinary conduit or outlet fixture. Within the central cavity of the cup-shaped casting, there is a round plug having an annular groove with inclined walls. This plug is held in place within the casting in such a manner as to prevent rotation, but to allow a slight amount of axial movement. At its lower edge the plug is provided with radially projecting tongues and the upper edge of the reflector has an inwardly turned flange provided with recesses corresponding to the tongues on the plug. The reflector is secured to the holder by placing it with the cut out portions of the flange in registration with the tongues on the plug. Then the reflector is turned so as to cause the flange to overlie the tongues and thereafter the plug is raised so as to firmly clamp the reflector between the tongue and a shoulder of the casting, by means of a screw extending through the walls of the casting and having a camming action on the inclined walls of the annular groove in the plug.

Further details of the invention, and further objects and advantages thereof will become apparent from the following description thereof, reference being made to the accompanying drawing, in which Fig. 1 is an elevation, partially broken away, and showing the reflector clamp in the holder. Fig. 2 is an axial section through the clamping device, and showing the reflector in position, but before it has been clamped. Fig. 3 is a similar view, partially in section, and showing the reflector removed. Fig. 4 is a perspective of the reflector clamping plug, and Fig. 5 is a perspective of the upper portion of the reflector.

Referring now to Figs. 1, 2 and 3 of the drawings, the device may be supported in any convenient manner, as from a conduit 10, having a threaded end portion, which engages a threaded portion 11 of the cup-shaped casting 12. Obviously, other means for supporting the casting could be employed, such as a horizontal conduit, extending into a horizontal opening in the casting. However, the method of supporting the casting forms no part of my present invention.

At the termination of the threaded portion of the cup-shaped casting, the interior cavity is enlarged, as at 13. At the lower portion of the cavity the casting is again enlarged to form a shoulder 14, and a flange 15 depending from the shoulder, and which will assist in preventing moisture and dirt from entering the interior of the holder, may also be provided.

Within the cylindrical cavity 13 of the cup-shaped casting, a cylindrical plug 16 (see Fig. 4) is mounted. The plug is loosely mounted to allow a slight amount of vertical movement, but no rotational movement, as by screws 17 and 18, which are threaded into the casting. The screws may have cylindrical shanks, as indicated at 19 (Fig. 2), and the heads of the screws may engage shoulders in cylindrical holes 20 in the plug. The plug is provided with an annular groove indicated at 25, and having a sloping or bevelled wall 26. To raise and lower the plug, a thumb screw 27 is threaded through the wall of the casting in such a manner that the end of the

screw 28 engages the bevelled wall 26. It will be seen that by turning the screw 27 inwardly, the plug will be cammed upwardly by the action of the screw against the inclined wall.

It is within the purpose of my invention to provide any coacting camming surface and cam which will move the plug longitudinally. Inasmuch as the plug does not rotate, the 10 camming surface need not be an annular groove except that I have found that a convenient form to construct. The other coacting member need not be a screw. I may use any camming pair and where a screw is 15 not used I provide other locking means.

In order to support the reflector, the plug is provided with outwardly extending tongues 30, three being shown in the present instance. The reflector 31 may be enamelled 20 and is provided with a cylindrical upper portion 32, and an inwardly extending flange 33, which is provided with cut-away portions, indicated at 34, spaced to correspond to the tongues 30 of the plug. In order to insert 25 the reflector in the holder, it is slipped over the tongues with the openings in registration with the tongues, and then the reflector is turned slightly, so that the flange 33 overlies the projecting tongues. The width of the 30 tongue 30 and the openings 34 is a small part of the circumference of the flange 33, so that the reflector may assume any radial position. In order to prevent the reflector from being turned too far, and thus coming 35 into registration with the tongues again, lips 35 may be formed at the edges of the openings in the flange. After the reflector is positioned and turned to the desired position, the screw 27 is turned inwardly, thus camming the plug upwardly, thereby clamping the reflector flange between the plug and the casting, and firmly holding the reflector 40 against rotation. If desired, a washer 36 of fiber or other suitable material may be placed 45 over the reflector flange to form a cushion between the flange and the shoulder 14 of the casting, to prevent chipping of the enamel on the reflector, and to provide a water-proof and dust-tight joint.

50 The lamp bulb 40 may be mounted in a porcelain socket 41 of any ordinary type, which may be secured to the plug by means of screws 42 extending through openings in the socket and threaded into the plug. Electricity may 55 be supplied to the socket through wires 43 and 44, which extend through the supporting conduit and through the central opening 45 in the plug. These wires are secured to the socket contacts by screws 46 and 47 in the usual manner.

60 From the foregoing description of a preferred form of my invention, it will be seen that I have provided an extremely simple holder for firmly and securely attaching a reflector to a lighting fixture. My holder can

be constructed economically and the reflector can be easily and quickly inserted or removed. Also, the electrical connections are completely enclosed and the entire construction is water-proof and dust-tight. Furthermore, in 70 my holder the reflector may be secured in almost any desired position,—a feature which is valuable when reflectors having other than circular shapes are employed.

I claim:

1. In a device of the character described, the combination of a cup-shaped member adapted to be supported from an electrical outlet and having a central cavity and a shoulder portion, a plug supported within the cavity of the cup-shaped member, means for supporting the plug to allow for a small amount of axial movement thereof and for preventing rotation thereof, said plug having a camming surface thereon, and said plug having projecting tongues at one end thereof, a reflector having a flange portion, said flange portion being provided with openings corresponding to the tongues on said plug, whereby the reflector may be slipped over 90 the tongues on said plug and turned so that the flanged portion overlies the tongues to support the reflector, and a screw extending through the walls of said casting and engaging the camming surface on the plug, 95 whereby inward movement of the screw will cause the plug to be moved in a direction to clamp the reflector flange between the tongues of the plug and the shoulder of the cup-shaped member.

2. In combination, a cup-shaped member having a central opening, said opening being enlarged at one end thereof, to form a shoulder, a plug within the central cavity of the cup-shaped member, means for supporting the plug to prevent rotational movement, but to allow axial movement thereof, tongues projecting from one edge of the plug and being disposed adjacent the shoulder of the cup-shaped member, a reflector having portions adapted to overlie said tongue and to be positioned between said tongues and said shoulder, and means extending through the wall of the cup-shaped member and engaging the plug to move the plug in a direction to clamp the reflector between the tongues and the shoulder.

3. A reflector holder comprising in combination a supporting member having a central cavity and an annular shoulder, a plug disposed within said central cavity, means for supporting the plug to allow a slight amount of vertical movement thereof, a bevelled surface of the plug, camming means extending through the wall of the supporting member and engaging said bevelled surface, whereby the plug may be raised and lowered, a reflector supporting lug extending outwardly from the plug and adjacent the annular shoulder of the supporting member,

whereby upward movement of the plug will cause the lugs to clamp a reflector flange between the lugs and the annular shoulder, and a fiber washer disposed between the reflector flange and the annular shoulder, thereby providing a water and dust-tight connection.

4. A reflector holder comprising in combination a supporting member having a central cavity and an annular shoulder, a plug disposed within said central cavity, means for supporting the plug to allow a slight amount of vertical movement thereof, and an annular groove in the plug having a bevelled wall, and camming means extending through the wall of the supporting member and engaging said bevelled wall of the annular groove, whereby the plug may be raised and lowered, a reflector supporting lug extending outwardly from the plug and adjacent the annular shoulder of the supporting member, whereby upward movement of the plug will cause the lugs to clamp a reflector flange between the lugs and the annular shoulder.

5. In a device of the character described, the combination of a supporting member having a central cavity and a shoulder portion, a reflector supporting member supported within said central cavity and having reflector supporting lugs adjacent said shoulder portion, and an annular groove having a bevelled wall, a screw extending through the wall of the supporting member and engaging said bevelled wall, whereby inward movement of the screw will cause the reflector supporting lug to be moved towards the shoulder, whereby a reflector may be clamped between the lugs and the shoulder.

6. In a reflector holding device, the combination of a member supported from an electrical outlet and having projecting tongues at one end thereof, a reflector having an annular flanged portion, said flanged portion being provided with openings corresponding to the tongues on the said member, the width of said openings being a small part of the circumference of the annular flange, whereby the reflector may be slipped over the tongues on said member and turned so that the uninterrupted portion of the annular flange overlies the tongues and supports the reflector in any radial position, and clamping means to prevent accidental rotation of the reflector.

7. In combination, a pair of coacting members, one member carrying shoulder portions and the other member carrying projections, a reflector having flanged portions adapted to overlie the projections, a camming surface on one of said members and means on the other of said members coacting with the camming surface, whereby the members are brought together longitudinally to hold the flanged portions between the projections and shoulder portions, and means for retaining the members in clamped relationship.

8. In a combined reflector holder and socket

support for an electric lamp, the combination of the fixed member in the form of a downwardly facing cup having an edge flange and a transverse surface within the flange, a movable member carried by the fixed member within said flange by means of studs screwed into the fixed member and projecting downwardly and loosely occupying holes in the movable member and having heads at their lower ends, whereby the movable member is capable of limited movement toward and from the fixed member, said movable member having projecting wings extending beneath the transverse surface of the fixed member, a reflector having a sleeve portion adapted to extend into the space bounded by said flange of the fixed member and provided with interrupted inturned flanges at its upper end, said reflector sleeve flanges being adapted to be passed between said wings of the movable member and then moved over them by rotary movement of the reflector sleeve, means apart from said studs for causing the movable member to approach the fixed member to clamp the reflector flanges between the wings of the movable member and said transverse surface of the fixed member, a downwardly extending socket and means for removably securing said socket to the movable member and said socket being adapted to stand within the sleeve of the reflector when the latter is in place.

9. A reflector holding device comprising in combination a member adapted to be supported from an electrical outlet and having a central opening and a flanged shoulder portion, a plug disposed within said central opening and having projecting lugs adjacent said flanged shoulder portion, and means operable through the wall of the member for moving said lugs without rotation toward said shoulder portion, whereby a reflector may be clamped between said lugs and said shoulder portion.

10. In combination, a pair of coacting members, one member carrying shoulder portions and the other member carrying projections, a reflector having flanged portions adapted to overlie the projections, a camming surface on one of said members and means on the other of said members coacting with the camming surface, said camming surface and coacting means being arranged to move the members together, whereby the members may hold the flanged portions between the projections and shoulder portions.

11. In a device of the character described, the combination of a supporting member having a central cavity and a shoulder, a plug having a sliding fit in the cavity and having projections disposed outside the cavity and adjacent the shoulder, a substantial portion of the plug lying within the cavity when the projections lie adjacent the shoulder, a reflector having a flange adapted to lie between

the projections and the shoulder, and means acting on one side of the plug for moving the supporting member and the plug together, whereby the contact between the plug and the 5 wall of the cavity keeps the parts from jamming.

12. In a device of the character described, the combination of a member adapted to be supported from an electrical outlet, another 10 member supported by the first member for longitudinal movement only, by pins carried by said first member and slidably engaging the second mentioned member, portions of one member overlying portions of the other 15 member, a reflector having a flange adapted to lie between the overlying portions of the members, and means additional to said pins to clamp the members in contact with said flange.

20 13. In a combined reflector holder and socket support for electric lamps, a fixed member, a movable member, means for guiding the members relative to each other for slight longitudinal movement only, means upon the 25 two members adapted to coact to hold the reflector therebetween, means for forcing the members into clamping relationship, and a lamp socket carried by the second member.

14. In a reflector holding device, the combination of a supporting member adapted to 30 be attached to an electric outlet and having an annular shoulder, a socket for holding a lamp, a portion rigid with the socket and extending into the supporting member and having 35 projections beneath said annular shoulder, vertical screws carried by the supporting member and extending freely through means rigid with the socket for preventing separation of the supporting member and socket 40 while allowing the socket to move toward the supporting member, a reflector having an in-turned flange adapted to overlie said projections and having spaces adapted to pass beyond the projections, and means for moving 45 the socket toward the supporting member without turning said screws, whereby to clamp the flange of a reflector between the socket and supporting member.

50 15. In a reflector holding device, the combination of a fixed member adapted to be supported on an electric outlet, a socket member, a portion rigid with the socket and having 55 projections beneath said fixed member, vertical screws carried by the fixed member, said socket member being mounted on said screws to move freely for a short distance toward and away from the fixed member, a reflector having a flange adapted to overlie said projections, and means for moving the socket 60 member toward the fixed member without turning said screws whereby to clamp the flange between the members.

65 16. In combination, a pair of coacting movable members attached together, one member carrying shoulder portions and the other

member carrying projections beneath the shoulder portions, a reflector having an interrupted flange adapted to be passed beyond and turned to overlie the projections, a camming surface on one of said members, and 70 a screw threaded in the other of said members and engaging the camming surface, whereby the members are brought together longitudinally to hold the flanged portions between the projections and the shoulder portions. 75

In testimony whereof, I hereunto affix my signature.

JOHN A. MCKAY.
